CABINET DOOR

Marvin A. Schott, 11628 Whittier,
Detroit, Mich. 48224

Filed Oct. 21, 1965, Ser. No. 87,713

Term of patent 7 years

(Cl. D33—1)

FIG. 1

FIG. 3

FIG. 2

FIG. 1 is a front elevation of a cabinet door showing my new design.

FIG. 2 is a perspective view of the same cabinet door.

FIGS. 3 and 4 are respective opposite end elevations of the cabinet door.

The rear of the cabinet door is a flat surface.

I claim:

The ornamental design for cabinet door, as shown and described.
